Des. 192,931
Patented May 29, 1962

192,931

CHILD'S ELEVATOR APPARATUS

Arvid V. Wuthnow, 546 E. Ave. A, Hutchinson, Kans.

Filed Apr. 17, 1961, Ser. No. 64,778

Term of patent 14 years

(Cl. D34—15)

Fig. 1.

Fig. 2.

Fig. 3.

Fig. 4.

FIG. 1 is a perspective view of the child's elevator apparatus, showing my new design.

FIG. 2 is a perspective view similar to FIG. 1 showing the elevator apparatus in a raised position.

FIG. 3 is a side elevational view thereof; and

FIG. 4 is a rear elevational view of the child's elevator apparatus.

I claim:

The ornamental design for a child's elevator apparatus, as shown.
